WALTER W. LANDSIEDEL, OF CINCINNATI, OHIO, ASSIGNOR TO REMINGTON RAND INC.,
OF TONAWANDA, NEW YORK

AUTOMATIC CARRIAGE RETURNING MEANS

Application filed September 19, 1927. Serial No. 220,389.

This invention relates to recording machines of the movable carriage type which are provided with manually controlled motor driven mechanisms. This invention has special reference to carriages having a motor driven return travel, such travel being manually controllable by the operation of a return key in which, upon the depression of the return key, the carriage will be returned by the action of the motor drive.

The main object of this invention is to provide an automatic throw for the return key mechanism of Dalton machines when the carriage reaches its limits of travel, thus eliminating the manual operation of depressing the return key.

Fig. 1 is a right side view of a machine of the type mentioned, with a part of the side plate broken away.

Fig. 2 is a partial section on the line 2—2 of Figure 1.

Fig. 3 is a partial section on the line 3—3 of Figure 1.

Fig. 4 is a partial front view of the right hand portion of the machine.

The machine on which this invention is shown is a well known Dalton adding machine which comprises a machine frame 11 housing the usual various calculating and registering elements operable under control of the keyboard 12, and upon which is mounted a laterally shiftable carriage 13. This machine is operatively connected with the usual motor 14 which operates the stroke and carriage return mechanism, the latter mechanism consisting of a clutch 15, a train of gears 16, and a vertical shaft 17 carrying a pinion 18 in mesh with a rack 19 on the carriage 13. The said clutch 15 is controlled by a clutch lever 20 (Figs. 1 and 2), which is mounted on the case of the clutch and when moved into the dot and dash position in Figure 2 will cause the motor to operate the shaft 17. The arrangement of gears is such that the shaft 17 will be rotated clockwise thus moving the carriage 13 to the right to the desired position where another mechanism, not shown herein, throws out the clutch by turning the said clutch lever

back to the position shown in full lines in Figure 2. The clutch lever 20 is thrown clockwise by a throw lever 21, pivoted at 22 and rocked clockwise by depression of the usual return key 23, (Fig. 1), the said return key lifting a link 24, (Figs. 1 and 2), connected to the left hand end of the throw lever and thereby lowering the right hand end, which acting upon a stud 25 in the clutch lever 20 imparts a clockwise throw to this lever.

The adding machine stands on and is removable from the frame in which the motor is mounted, the adding machine being one unit and the motor with its supporting frame and the clutch-case and gearing being another unit, as explained in Letters Patent No. 1,209,858, and No. 1,270,845, and exemplified by Dalton machines long in public use. The adding machine can be lifted bodily off of the motor frame. The hub 22a into which the pivot pin 22 of lever 21 extends and by which that lever is supported is fast at its front end on the frame of the adding machine.

Means is provided for operating the throw lever automatically as the carriage reaches its farthest forward or left hand position. This means comprises a cam lever 27 (Figs. 1 and 3), pivoted on the machine frame 11 and urged clockwise by a spring 28 fastened to the lever and the machine frame. A cam roll 29 is rotatably mounted upon a bent lip on the end of the upper arm of the lever, the said arm and lip protruding thru the machine frame.

A throw cam 30 is secured to the under side of the guide comb 31 near the right hand end of the same, the said guide comb being rigid with the carriage 13. The cam is preferably located to move into cooperative relation with the cam roll when the carriage 13 reaches its extreme left position, thereby throwing the cam lever 27 counter-clockwise. A slide link 32, (Figs. 1 and 2), pivoted to the end of the lower arm of the lever 27, is slidably mounted on a bracket 33 which has a stud 34 projecting thru a slot 35 in the slide link. The slide link is also provided with a lip 36, which cooperates with a pin 39 in the

throw lever 21 by means of which the downward action of the slide link, received from the lever 27, is transferred to the lever 21 which is thrown in a clockwise direction causing the functioning of the return mechanism as heretofore described.

The return of the carriage releases the lever 27, which under the tension of the spring 28 returns to its home position as shown in Figure 1. The slide link 32 is carried with it, of course. The return action of this lever system is limited by the extremity of the slot 35 striking the stud 34.

While the invention has been shown in one form of embodiment and as applied to a particular type of machine, it is to be understood that it may take other forms and be applied to other types of machines, all falling within the scope of the claims.

When the adding machine is lifted from or set on the motor-supporting frame, of course the lever 21 is removed from or placed in its proper position with relation to the clutch lever by this mere act without requiring any special skill or care on the part of the user of the machine.

What is claimed is:—

1. In a machine of the class described, the combination with a laterally shiftable carriage, motor driven means for returning it to its home position, a carriage return key and a device operated by said key for closing a clutch to cause the motor to return the carriage, of a cam plate 30 mounted on said carriage, a lever 27 in the nature of a follower operated by said cam at a given point in the carriage travel and a link 32 operated by said lever and acting directly on said key operated device to close the clutch.

2. In a machine of the class described, the combination of an angularly movable clutch-closing device having a horizontal pivotal axis, a pivoted lever at one side of said device the pivotal axis of this lever being horizontal, and a downwardly movable carriage-actuated slide, said device having on it a lateral projection, said lever also having a lateral projection and extending over and normally making contact with the lateral projection of said device, and said slide extending over and normally resting on the lateral projection of said lever.

3. In a machine of the class described, the combination of an angularly movable clutch-closing device having a horizontal pivotal axis, a pivoted lever at one side of said device the pivotal axis of this lever being horizontal, and a key-actuated pull-link connected to said lever, said device having on it a lateral projection, and said lever extending over and normally making contact with said projection, and the pivot of said lever being between the connection with the pull-link and the contact with the projection.

4. In a machine of the class described,

which machine comprises an adding machine and power-actuated operating means forming distinct and separable units, the combination of a clutch-closing device mounted on the frame of the operating means, a lever mounted on the frame of the adding machine, and lever-actuating means embodied in the adding machine.
